UNITED STATES PATENT OFFICE.

MARIUS LATOUR, OF PARIS, FRANCE.

TELEPHONE REPEATING SYSTEM.

Application filed April 28, 1923. Serial No. 635,280.

To all whom it may concern:

Be it known that I, MARIUS LATOUR, a citizen of the Republic of France, residing at Paris, France, have invented certain new and useful Improvements in Telephone Repeating Systems (for which I have filed an application in France on April 22, 1922, No. 15,867), of which the following is a specification.

10 The present invention relates to improvements in two-way amplifying systems as applicable to interurban telephonic communication and is more particularly described with reference to the accompanying dia-
15 grammatic drawings 1 to 3 inclusive.

Figure 1 illustrates the principle of operation of the invention as applied to link a four-wire interurban line with a two-wire subscriber's line at each of its extremities.

20 Figure 2 illustrates a more elaborate form of the invention as applied to link a four-wire interurban line with a two-wire subscriber's line.

Figure 3 illustrates the invention as applied to an ordinary interurban line.

Figure 4 is a view showing the source of direct current in each cathode lead connected with the secondary windings of the transformer.

30 In Figure 1 the interurban line is represented by the two pairs of conductors 1, 2, each comprising a unilateral amplifying relay R_1 , R_2 , respectively, serving to amplify the microphonic currents in the directions indicated by the arrows.

A subscriber's instrument comprising a telephone receiver 6, an induction coil 7, a microphone 8 and a cell 9, is connected to one extremity of the interurban line through 40 a vibrator 5 which alternately makes contact with the line terminals 3 and 4. A similar subscriber's instrument is connected to the other extremity of the interurban line through a vibrator 5' which alternately makes contact with the line terminals 3' and 4'.

In Figure 1, similar numbers denote similar organs, the right-hand numbers being affected with an index merely to differentiate the relative positions of the organs with reference to the interurban line.

If we consider the vibrator reeds 5 and 5' as being respectively in contact with the terminals 3 and 3', it is obvious that the telephone receiver 6' will be traversed by the speech currents emitted by the microphone

8 and amplified in transit through the amplifying relay R_1 . Reciprocally, if we consider the vibrator reeds 5 and 5' as being respectively in contact with the terminals 4 and 4', it is obvious that the receiver 6 will be traversed by the speech currents emitted by the microphone 8' and amplified in transit through the amplifying relay R_2 .

If the vibrators 5 and 5' operate synchronically, a coherent communication may be established between the two extreme subscribers providing the vibrators operate at a sufficiently high frequency. It is seen that this system amounts to having a unilateral amplifying repeater the direction of which is rapidly alternated.

The synchronous operation of both vibrators could be arrived at by means of a special arrangement, but in view of the electrostatic capacity of the telephone line, which line is usually a long distance cable, this synchronism need not be established as the electrostatic capacity delays the effective charge produced upon the conductors by the current passing through the closed vibrator until the other vibrator becomes effective. In event of the inherent line capacity being insufficient, additional condensers may be branched at the extremities of the interurban line.

In Figure 1, the vibrators 5 and 5' are indicated merely by way of example and the present invention does not purpose to restrict itself to the exclusive use of vibrators of the type described.

Figure 2 illustrates the present invention in its most elaborate form. In this form, the arrangement represented therein is inserted between each subscriber's two-wire line and the corresponding extremity of the four-wire interurban line described with reference to Figure 1. In accordance with the invention, the commutating action of the vibrator described above is obtained by means of two thermionic tube relays of the conjugated type the anode circuits of which are supplied with alternating current.

In Figure 2, the subscriber's line A is branched to the primary winding 1 of the subscriber's input transformer the secondary winding 2 of which is connected to the grids of tubes 3 and 4 in such a manner as to bring each grid to a potential opposite in sign with reference to each other. The subscriber's output transformer primary winding 7 is inserted in the anode circuits

of tubes 3 and 4 in such a manner as there results, at any instant, no induced current in coil 8 providing the anodes of tubes 3 and 4 take equal currents. Under these conditions, the secondary winding 8 of the subscriber's output transformer can only give rise to amplified telephonic currents which are sent on to one pair of conductors L of the four-wire interurban line. The terminals of the other pair of interurban line conductors L' are connected to the primary winding 1' of the line input transformer the secondary winding 2' of which is connected to the grids of tubes 3' and 4' in such a manner as to bring each grid to a potential opposite in sign with reference to each other. The line output transformer primary winding 7' is inserted in the anode circuits of tubes 3' and 4' in such a manner as there results, at any instant, no induced current in coil 8 providing the anodes of tubes 3' and 4' take equal currents.

The cathodes of the left-hand set of tubes are brought to incandescence by means of a battery 5, those of the right-hand set being heated by a similar battery 5'.

The anode circuits of both sets of thermionic tube relays are supplied with alternating current from the secondary windings 6, 6' of a supply transformer, or by any other appropriate alternating current generator, in such a manner as to have, at any instant, each set of anodes subjected to a voltage opposite in sign with reference to each other.

Under these conditions, it will be seen that, at any instant, there is only one set of tubes which is in an operative condition. This is equivalent to the action of the vibrator of Figure 1 in which the subscriber's line is alternately branched onto the output and input pairs of the interurban conductors. In order to shorten, during each half cycle, the length of time during which each set of anodes is subjected to positive potential, a source of direct current may be inserted in each cathode lead. In Fig. 4 I have shown such modification. A source of direct current is located in each cathode lead from the secondary winding 6 and 6'.

If it is desired to obtain terminal amplification ordinary unilateral amplifiers may be inserted between the subscriber's output transformer secondary winding 8 and its corresponding line terminals L or between the line input transformer primary winding

1' and its corresponding line terminals L' having due regard to the direction of amplification.

If we do not take the electrostatic capacity of the telephone line into account, it is clear that the working of this system can only become efficient as starting from an anode circuit feeding current frequency of about 2000 cycles. In view of this line capacity however, we may advantageously shorten, during each half cycle, the length of time during which each set of anodes is subjected to positive potential by inserting a source of direct current in the cathode lead of each winding 6, 6', as described above. This arrangement has the advantage of facilitating a reduction in the feeding current frequency.

Figure 3 illustrates the commutating arrangement of Figure 2 operated as a two-way repeating amplifier inserted at some intermediate point of an ordinary two-conductor interurban line. In Figure 3 and in Figure 2, similar numbers are used to designate similar organs. The operation of the arrangement described in Figure 3 is similar to that of a unilateral repeating amplifier the direction of which is rapidly altered.

What I claim and desire to secure by United States Letters Patent is:

1. In an interurban telephone communication system, a transmission line consisting exclusively of two pairs of speech conductors, each pair including a uni-lateral amplifying repeater, a two-conductor subscriber's line at each extremity of the four-wire interurban line, and means located at the extremities of the pairs of speech conductors and operating concurrently to alternately branch said subscribers' lines to either pair of interurban conductors at a sufficiently high frequency to establish a two-way communication.

2. An interurban telephone communication system consisting of two pairs of interurban conductors, each pair including a uni-lateral amplifying repeater, a two-conductor subscriber's line at each extremity of the four-wire interurban line, and two sets of connected pairs of balanced thermionic tube relays supplied with alternating current to alternately branch said subscriber's line to either pair of interurban conductors.

In testimony whereof I affix my signature.

MARIUS LATOUR.
